UNITED STATES PATENT OFFICE.

ALGOT A. WICKLAND, OF CHICAGO, ILLINOIS.

CUPOLA-CHARGING MACHINE.

Application filed March 20, 1922. Serial No. 545,314.

To all whom it may concern:

Be it known that I, ALGOT A. WICKLAND, a citizen of the United States of America, residing at Chicago, in the county of Cook 5 and State of Illinois, have invented certain new and useful Improvements in Cupola-Charging Machines, of which the following is a specification.

My invention relates to cupola charging 10 machines for use in gray iron foundries.

The object of my invention is to provide an efficient device for handling a large tonnage of already weighed charges of iron and coke previously arranged on the charging 15 floor and to provide mechanical means for charging said material into the cupola in even layers, in a simple and expeditious manner.

A further object of this invention is to 20 eliminate, as far as possible, manual labor and the attendant fatigue, discomfort and exposure of the operators to the high furnace temperatures that are incurred while charging by hand.

Another object is to provide a machine 25 which will permit storing the loaded charging cars on the floor and from whence the material may be conveyed to the cupola and charged as required, with a minimum amount 30 of manual labor. The charging machines commonly in use are located in a fixed position in front of the cupola and the operator has no means of controlling or spreading the charges as the material is dumped into 35 the cupola. The result of this method of operation means that the charge, which consists of alternate layers of iron and fuel are distributed unevenly, which is detrimental, if an efficient operation of the cupola is desired. 40

In the operation of small foundries it is considered good practice to deliver the necessary material to the charging floor before the cupola is started. The material is then 45 weighed up and charged by hand as the melting progresses. The material is transported from the yard bins in hand trucks or wheelbarrows and an elevator is used for lifting the trucks to the charging floor where 50 the material is dumped on the floor in separate piles. The material is then weighed up and charged in the cupola. This system calls for a great deal of costly hand labor, which my invention will obviate. With a 55 charging machine, the charges may be weighed up in the yard in suitable charg-

ing cars, thence conveyed to the charging floors and either left on the floor for reserve or discharged directly in the cupola. Other charging machines, being of the stationary 60 type, cannot be used for the purpose of placing the cars or containers on the floor.

An additional object of this invention is to provide a machine of the simple design and sturdy construction necessary to withstand hard usage in the hands of unskilled 65 operators.

Other objects and advantages of the invention will be apparent from the following description when considered in connection with 70 the accompanying drawings illustrating a preferred embodiment thereof, in which—

Figure 1 is a longitudinal section showing the cupola, overhead supporting framing and tilting mechanism, the supports for the 75 circular track, air and electric connections being omitted for clearness.

Figure 2 is a plan view of the cross-head and pivoted bearing, taken on line 2—2 Figure 1. 80

Figure 3 is a plan view of the cradle or platform, taken on line 3—3, Figure 1.

Figure 4 is a plan view showing the supporting track wheels, gearing and framing, 85 taken on line 4—4, Figure 1.

Figure 5 is a plan of the complete assembly and a cross section of the cupola. This view also indicates the relative arrangement of the charging cars when placed on the floor for storage. 90

Figure 6 is an end elevation of the complete machine with the charging car shown in position.

Figure 7 is an elevation showing the lifting cylinder and cross section of the trolley 95 frame, taken on line 7—7, Figure 5.

Figure 8 is an elevation and cross section, taken on line 8—8, Figure 5, showing the motor, spur gearing and structural framing.

Figure 9 is an enlarged longitudinal cross 100 section of the platform or cradle. The dash and dotted lines indicate the position of the charging car.

Figure 10 is a transverse section of the platform, taken on line 10—10, Figure 9. 105

Figure 11 is a plan view of a modified construction intended for use in serving one or more cupolas.

In the drawings, wherein I have illustrated the preferred embodiment of my invention, 110 30 indicates the charging floor, at one end of which the cupola 29 is arranged;

the opening into the cupola being slightly above the floor level. Arranged above the floor a suitable distance, is a pair of parallel tracks 1—1, these tracks being connected together at their ends, and adapted to have the track wheels 2^a ride thereon.

Trolley members 2 carry the track wheels 2^a, and the trolley members 2 also carry downwardly and forwardly extending framing 3, which in turn carries the car receiving platform 4 at its lower end. The lower end of the framing 3 extends in advance of the upper end relative to the charging opening of the cupola, for a purpose to be more clearly hereinafter described. One end of the inclined track 1 is supported by a crosshead 9 which also forms a pivoted thrust bearing for a kingpin 10. A sleeve having an integral plate 11 is supported on I-beams 22 arranged to extend transversely of the track members 1, said I-beams being preferably a part of the steel work of the building itself. The opposite end of the track is supported at an elevation below the pivoted end 25 so as to form an inclined track upon which trolley and framing may be moved. The lower end of the inclined track is supported upon members 12 and track wheels 15. These last mentioned wheels are carried by shafts 14, which in turn are driven by any suitable means, as for instance by beveled gearing operating in conjunction with a shaft 13 connecting the beveled gearing. The shaft 13 may be driven by a spur gear 17 and a pinion 16, directly connected to a source of power, as for instance a motor as shown Fig. 8.

The trolley frame 2 consists of two parallel members having a rigid cross-bracing 40 therebetween to form a rectangular frame, provisions being made for connections with the trolley framing 3. Any suitable means may be provided for resisting the vertical movement of the trolley wheels, as for instance guides or the like, but these trolley wheels are always free to travel longitudinally of the track members 1.

A compressed air cylinder 8 is rigidly connected at one end to the trolley frame and has a piston rod insertable thereinto at the other end, the piston rod being secured or anchored to the crosshead 9. It is obvious that when air is admitted into the cylinder 8 the cylinder and not the piston will be actuated and thereby cause the trolley and framing carried by the cylinder to be moved together therewith.

The members 12 are braced by a yoke 18 extending therebetween and thereabove to clear the cylinder 8 and which serves the purpose of giving lateral stiffness and rigidity to the inclined track members 1.

A circular track 23 is provided and upon which the wheels 15 are movable and carrying the overhead track structure. Any

means may be provided for supporting these tracks, as for instance floor columns, or these tracks may be suspended from above. A car-carrying cradle or platform 4 is adapted to be arranged at the lower end of the framing 3, said platform comprising a floor plate 4^a upon which the car 21 is adapted to rest, said floor plate being riveted or otherwise rigidly secured to a pair of parallel side members 4^b spaced to clear the car (see Figs. 6 and 10). A member 5^a is connected across one end of the plates 4^b and closes said end and limits the movement of the car in one direction. Hinged to the portion 5^a by means of a pin 5^c is a U-shaped member 5, shown more particularly in Figs. 3, 9, and 10. The cross-section of the legs of said U member being preferably angle-shaped. The legs of the member 5 extend substantially the full length of the platform, and the free ends are extended downwardly thereof, as shown in Fig. 9.

Pivottally secured to the free ends of the U member 5, as at 6^a, is a bail 6. A hoist 7 is connected at one end to the movable trolley 2 and is connected at its other end to the bail 6 so that said hoist may be operated to raise the bail and tilt the U-shaped member, as shown in dotted lines in Fig. 1.

It is obvious that the flanges and ribs provided on the U-shaped member will engage the car 21 placed on the platform 4 and prevent the same from moving forward or sideways when the car is tilted. The charging cars 21 may be constructed in any convenient shape or size to suit the material to be handled, but four-wheel cars are preferable to those having a lesser number of wheels.

The framing members 3 provide a very rigid bracework between the trolley and the platform and are constructed with the necessary clearance so that they will not interfere with the movement of the car, platform, or lifting cylinder.

The operation of the device is as follows: The loaded cars, or containers, are placed on the platform 4, as shown in full lines in Fig. 1. An air-controlled valve indicated at 20 is opened to admit air to the cylinder, and the trolley then moves forward, advancing the platform to the position indicated in dotted lines. Air is then admitted to the lifting cylinder or hoist 7, which will move the lifting bail and the U-shaped tilting frame 5, tilting the car forwardly, as shown in dotted lines, causing the entire contents of the car to drop within the cupola opening.

In order to spread the charges evenly, the car may be moved to any desired position, viz it may be advanced, retarded, or tilted to a greater or less degree at the will of the operator. To further insure an even distribution of the material in charging, the machine may be swung to the positions indicated by the lines C and D Fig. 5, so that

the car may be more accurately dumped into the desired position in the cupola. It is evident that by this method the charges may be distributed uniformly and evenly over the entire area of the cupola, which is of utmost importance in obtaining a uniform mixture of iron and insuring the most efficient operation of the cupola. After the contents of the car are emptied, the machine is returned 10 to normal position shown in full lines in Fig. 1 by exhausting the air in both cylinders 7 and 8.

The machine may also be used for "spotting" empty or loaded cars on the charging 15 floor. This is done by placing the cars on platform 4, then admitting air to the cylinder 8 to advance and lift the platform off the floor sufficiently to clear. It may then be moved in a circular path, as shown in 20 Fig. 5.

When the air is released the platform returns to the floor, and the car may be taken off and left on the floor in readiness for 25 charging. The dot and dash lines shown in Fig. 5 indicate one of the extreme positions of the platform when used for conveying cars intended to be left in storage.

It is to be noted that when the machine is 30 in the normal position shown in full lines in the drawings the platform 4 is directly in front of the cupola and is firmly resting on and entirely supported by the charging floor 30. It is also to be noted, and is extremely important, that the platform is advanced toward the cupola opening relative 35 to the overhead trolley structure movable therewith, that is, the platform is quite a distance nearer the cupola than the trolley. This is in order that the platform and tilting mechanism may enter and operate entirely within the cupola door or opening, as 40 shown, and without in any way over-exposing the moving parts of the operating cylinder to the heat of the gases or causing interference of the overhead track or structure 45 with the cupola shell.

The device shown in Fig. 11 is substantially similar to that previously described except that the trolley is arranged to move 50 along a pair of parallel track members 23^a, making the device extremely desirable where a series of cupolas 29^a are arranged in a row, as shown. It is obvious that there will be no pivoting of the trolley about one of the 55 track members 23^a as in the previously described modification.

What I have invented and desire to claim as new is:—

1. In a cupola charging machine, an inclined overhead track structure, a fixed pivot bearing supporting said track structure at one end, a radial track at the opposite end of said inclined track structure upon which said inclined track structure is movably supported, a trolley frame movably supported 60 by said inclined track structure, a platform rigidly suspended from said trolley frame and means on said platform to receive, hold and discharge portable containers placed thereon. 70

2. In a cupola charging machine, an inclined overhead track, a trolley frame adapted to travel on said track, a platform rigidly suspended from said track frame, a U-shaped member pivoted to said platform 75 adapted to engage and discharge portable containers placed on said platform and power means for tilting said U-shaped member, substantially as described.

3. In a cupola charging machine, an overhead bridge structure having an inclined track thereon, a trolley frame adapted to be movably supported and guided on said track, a platform rigidly connected to said trolley, said platform having a U-shaped 80 member hinged thereon which is adapted to engage and tilt receptacles to discharge their 85 contents.

4. In a cupola charging machine comprising an overhead structure provided with an inclined trolley track, a trolley frame mounted for movement along said track, a platform rigidly suspended from said trolley, and means on said platform adapted 90 to engage and discharge portable receptacles placed on said platform. 95

5. In a cupola charging machine an overhead bridge structure, an inclined track supported thereon, a trolley frame movable on said track, a car platform rigidly suspended 100 from said trolley in an advanced position thereto.

6. In a cupola charging machine, an overhead bridge structure, an inclined track supported thereon, a trolley frame movable on said track, power means for moving said trolley frame along said inclined track, and a car platform rigidly suspended from said trolley frame in an advanced forward position. 105

ALGOT A. WICKLAND.
